UNITED STATES PATENT OFFICE.

WALTER LORD, OF TODMORDEN, COUNTY OF YORK, ENGLAND.

COTTON-OPENER.

SPECIFICATION forming part of Letters Patent No. 242,461, dated June 7, 1881.

Application filed December 13, 1880. (No model.)

To all whom it may concern:

Be it known that I, WALTER LORD, a subject of Great Britain, residing at Todmorden, in the county of York, England, have invented 5 certain new and useful Improvements in Cotton-Openers; and I do hereby declare the following to be a full, clear, and exact description of the invention, such as will enable others skilled in the art to which it appertains to make 10 and use the same, reference being had to the accompanying drawings, and to letters or figures of reference marked thereon, which form a part of this specification.

This invention relates to exhaust-openers for 15 cotton; and it consists in the construction and combination of parts, hereinafter particularly set forth and claimed.

Heretofore in the operation of cotton-openers of this class, when "knocking off," as it is 20 termed, takes place by the shifting of the knocking-off lever by the operator the flow of cotton is arrested, while the draft through the feed-tube continues, the result being that cotton accumulates in the latter and is formed in 25 to thick places which produce an uneven lap, and the density and form of the sheet delivered to the beater varies constantly.

The purpose of my present improvement is 30 to avoid this objectionable feature by intermittently the suction through the feed-tube simultaneously with the cessation of the flow of cotton in knocking off, and vice versa; and it consists in providing the said feed-tube, at or near 35 its junction with the beater, with a valve or its equivalent, operating with such tube, and with an opening in the same to permit of entrance 40 of external air to the opener when knocking off (by which is understood the act of suspending the feeding devices and calender-rolls of the machine) takes place, to interrupt the flow 45 of cotton through the feed-tube, or to close such opening and restore the draft to the interior of the tube, when the machine resumes its functions, the valves being connected with 50 the knocking-off lever by suitable intervening mechanism, in order that the motion of the lever may be automatically transmitted to such valves to operate them as occasion requires.

The drawings accompanying this specification 55 represent, in Figure 1, a sectional elevation of a cotton-opening machine embracing

my improvement; Fig. 2, a horizontal section; Fig. 3, a vertical section of the draft-tube and valves, the machine being a combined opener and lapper; and Fig. 4 a longitudinal view of 55 the lapper employed with my invention.

In these drawings, A represents the portion of a combined cotton opening and lapping machine known as the "conical beater," and A' the lapping portion of the machine, the first 60 consisting of a horizontal shaft provided with a series of radial arms gradually diminishing in length from front to rear of the shaft, and surrounded by a conical grid or barred casing, and the whole being contained within a suitable structure or box, into the bottom of which impurities from the cotton are deposited, while the draft or feed tube which supplies the conical beater, or its equivalent, is shown at B as 65 communicating at its lower end with the feed 70 end B' of the beater, and the knocking-off lever of the machine at C'.

The delivery end of the conical beater is provided with a rotary fan, D, to induce a current of air through it and the draft-tube, such fan, 75 with the fan employed to exhaust the air from the dust cages of the machine, serving to draw the cotton through the latter.

I provide, as shown in the present instance, 80 in the lower end of the feed-tube, which at this point is rectangular in cross-section, two oppositely-disposed apertures, b c, which, when open, permit of free entrance of air to the interior of the opener.

d e in the accompanying drawings represent 85 twin valves or gates formed of thin plates of metal, which together constitute an area greater than that of the portion of the tube enclosing them, each valve being secured at its outer edge to a horizontal shaft, f g, which is 90 mounted in bearings in the walls of the tube, immediately below the opening.

The apertures b c are each of somewhat less area than one of the valves, and are so arranged that when such valves are turned downward (or upward, if so arranged) they (the apertures) shall be closed by the valves and restore the draft or suction to the interior of the draft-tube, while if the valves are raised the apertures are opened and external air permitted to enter the apertures b c, the result being that the draft or suction through the 95 100

tube is broken, and the flow of cotton thereby interrupted.

The valves may be operated by hand, but I prefer to operate them automatically by the movement of the knocking-off lever; and to effect this I proceed as follows: To the side of the external rear end of the machine, and below the handle of the lever, I pivot a bell-crank lever, *h*, as shown at *i*, the end of the upper and horizontal arm, *j*, of this lever being connected with the handle of the lever *C'* by a rod or link, *k*, while the end of its lower and vertical arm, *l*, is connected, by a long horizontal rod, *l'*, with the corresponding arm *m* of a second bell-crank lever, *n*, pivoted to the side of the extreme opposite or front end of the machine, as shown at *o*, the end of the upper arm, *p*, of this lever being in turn connected, by a vertical rod, *q*, with the inner and free end of a sectoral plate, *r*, arranged outside of the feed-tube, and affixed at its opposite end to the end of the shaft *g* in such manner that vibratory motions of the crank-arm *p* shall effect the raising and lowering of the said shaft, and of the valves *d* and *e*. A sectoral toothed rack, *s*, is cut upon the periphery of the plate *r*, and meshes with a second rack, *t*, cut upon the periphery of a second sectoral plate, *u*, which is affixed at its outer end to the extremity of the opposite shaft, *f*, the whole being so arranged that both the valves *d* and *e* are raised and lowered at the same time. It will thus be seen that the act of lowering the lever *C'* in the act of knocking off operates, through the agency of the bell-crank levers *h* and *n*,

and rods *k* and *l'*, and *q*, to raise the valves *d* and *e*, and open the apertures *b c*, and admit external air to the opener, with the effect of intercepting the flow of cotton through the tube.

A raising of the knocking-off lever has the effect of lowering the valves *d* and *e* and closing the apertures *b c* and restoring the draft to the tube *B*.

Though I have described my improvement as applied to a combined opener and lapper, it is of course equally applicable to an opener without the lapper.

I do not restrict myself to the precise arrangement of the valves and openings as herein described, nor to the details of mechanism connecting them with the knocking-off lever, as it is evident these may be varied to a considerable extent without departing from the essential feature of my invention.

Having thus fully described my invention, what I claim as new, and desire to secure by Letters Patent, is—

In a cotton-opener, the combination of the draft or feed tube with the knocking-off lever, and mechanism, substantially as described, which operates automatically to interrupt or restore the draft through said tube, as and for the purpose set forth.

In testimony whereof I affix my signature in presence of two witnesses.

WALTER LORD.
